INVENTOR.

UNITED STATES PATENT OFFICE.

FRANK COBARUBIA, OF SACRAMENTO, CALIFORNIA.

RETURNING HOOP.

1,270,378.

Specification of Letters Patent. Patented June 25, 1918.

Application filed November 14, 1917. Serial No. 202,058.

To all whom it may concern:

Be it known that I, FRANK COBARUBIA, a citizen of the United States, residing at Sacramento, in the county of Sacramento and State of California, have invented a certain new and useful toy—a Returning Hoop; and I do declare the following to be a clear, full, and exact description of the same, reference being had to the accompanying drawings and to the characters marked thereon.

My invention relates to an improvement in a toy, designed for the instruction, entertainment and amusement of children, the object of the invention being to produce a hoop, operated in conjunction with a grooved handle and elastic cord, which will return to the operator when thrown upon the ground some distance away, and when used with the stanchion and fan in the center of the hoop, will return in like manner when thrown into the air.

A further object of the invention is to produce a simple and inexpensive toy and yet one which will be exceedingly effective for the purposes for which it is designed.

These objects I accomplish by means of such structure and relative arrangement of the parts as will fully appear by a perusal of the following specifications and claims.

On the drawings, similar characters of reference indicate corresponding parts in the several views.

Figure 1 is a full view of the toy, with elastic cord wound around the hoop in position to be operated.

Fig. 2 is a view of the grooved handle with the elastic cord attached.

Fig. 3 is a view of the hoop without the stanchion and fan.

Fig. 4 shows the stanchion detached from the hoop.

Fig. 5 is a sectional view of the hoop, showing the concave groove and the ovate-oblong hole through the hoop for receiving the elastic cord.

Fig. 6 shows the small fan painted in variegated colors to be fastened to the stanchion in the center of the hoop.

Referring now more particularly to the characters of reference on the drawings, the numeral 1 designates the hoop, to be made of wood or suitable metal, numeral 2 the grooved handle, and numeral 3 the elastic cord which is fastened to the end of the handle by passing through holes.

The numeral 4 shows the stanchion, to which is fastened the fan 5, the said stanchion to be placed in the center of the described area of the hoop and fastened on the inside of the rim.

To operate the toy, the knot on the end of the cord 3 is inserted in the ovate-oblong hole 6, and wound around the hoop 1 1 1, following the concave groove 6 9. The hoop is then placed in the groove 7 in the handle 8 8, and held by the hand, the operator giving the toy a toss, at the same time releasing the hoop, but retaining the grip on the handle, and as the hoop leaves the grooved handle the unwinding of the elastic cord will force the hoop to revolve in the reverse direction, and in a perpendicular position, causing it to take traction on the ground and return with increasing speed to the operator.

To operate the toy in the air, the fan 5 is attached to the stanchion 4, which is then placed in the center of the hoop, with the fan in a plane at right angle to the plane of the sides of the hoop, as shown in Fig. 1. Operating as before the hoop is tossed into the air in such manner that it will revolve in a perpendicular position, the colored fan in the center of the hoop, revolving at right angle thereto, giving an added attraction, and striking the ground will take traction and return to the operator.

I am aware that prior to my invention hoops, grooved handles and elastic cords have been made; I therefore do not claim such broadly, but what I claim as being new, is:

1. The combination, in a toy, of a hoop having a concave groove around the outside of the rim, and an ovate-oblong hole in the rim, substantially as described.

2. In a toy, the combination of a hoop with a handle, the said handle having a groove in one side and an elastic cord fastened to one end, by passing through a hole in the handle, and having its other end detachably connected to said hoop substantially as described.

3. The combination, in a toy, of a hoop having a concave groove around the outside of the rim, said hoop being provided with a stanchion, to which is attached a variegated fan, adapted to be detachably fastened to the inside of the rim in such manner that the fan will be in the center

of the described area of the hoop, and at right angle to the planes of its sides, all to be operated in conjunction with a grooved handle and elastic cord, substantially as specified.

4. In a toy, the combination of a hoop having an ovate-oblong hole, with a grooved handle and elastic cord, disposed to be operated in conjunction with each other, a knot on the end of the elastic cord adapted

to be inserted in the ovate-oblong hole, said cord being wound around the hoop, following the concave groove, the said hoop being then placed in the groove in the handle to be tossed away, the unwinding cord giving 15 the hoop a reverse movement causing it to return to the operator, all substantially as set forth.

FRANK COBARUBIA.
